(57) **CLAIM**

The ornamental design for a display panel with indicator for elevator, as shown and described.

DESCRIPTION

FIG. 1 is a front, top and right side perspective view of an display panel with indicator for elevator, showing my new design;

FIG. 2 is a front elevational view thereof;

FIG. 3 is a rear elevational view thereof;

FIG. 4 is a right side elevational view thereof;

FIG. 5 is a top plan view thereof;

FIG. 6 is an alternate front elevational view showing the changed state 1; and,

FIG. 7 is another alternate front elevational view showing the changed state 2.

The broken lines in all views are shown for the purpose of illustrating portions of the article and form no part of the claimed design. The alternate long and short dash lines in all views which define the bounds of the claimed design form no part thereof.
